TELEGRAPH TRANSMITTER

Fritz Hennig, Berlin-Siemensstadt, Germany, assignor to Siemens & Halske, Aktiengesellschaft, Siemensstadt, near Berlin, Germany, a corporation of Germany

Application May 9, 1940, Serial No. 334,181
In Germany February 8, 1939

10 Claims. (Cl. 178—5)

This invention pertains to printing telegraph systems and more particularly to telegraph systems and apparatus adapted to be operated under the control of key levers.

In telegraph systems involving apparatus for recording characters by a series of elemental areas of positive and negative surfaces, transmitting apparatus has been employed wherein each letter, symbol, or character is analyzed into a succession of constituent areas, and a code set of corresponding character embodiments are constructed, which embodiments then are selected under control of a keyboard. In accordance with such scanned or analyzed embodiments, electrical impulses are generated which cause corresponding operation of recording apparatus of the form disclosed in United States Patent No. 2,000,083 to form the characters in line.

The principal object of this invention is the provision of a practical and inexpensive key controlled facsimile telegraph wherein the key operations are coordinated cyclically with the transmission of the signal impulses for each character.

Another object is to provide, in a keyboard controlled facsimile telegraph transmitter, a means normally operable in regularly recurring cycles to coordinate the operations of a plurality of constantly rotating transmitting elements and a corresponding plurality of key operated mechanisms operable in irregularly recurrent cycles.

The above and other objects of the invention are achieved through the provision of a novel keyboard mechanism for controlling sensing members associated with constantly rotating code discs, and timing means for coordinating the operations of the keyboard and rotating code discs. An operated key lever controls the selection of a corresponding sensing brush. Individual to each brush is a code disc designed in accordance with a method of a prescanning in which the characters or symbols to be transmitted are divided into any desirable number of sensing units or areas. The several unit areas thus created are assigned in order of scanning to the periphery of the code disc. Inasmuch as the code discs rotate continuously by power communicated thereto from a continuously rotating motor and the brushes are selectively operated in accordance with the operation of the key levers, impulses representative of the positive and negative surfaces of the character code disc will be transmitted, which will be effective at the receiving end of the system to record a character in accordance with the pattern of the character formed on the periphery of the code disc then

effective for the transmission of the characteristic impulses.

A better understanding of the present invention may be had from the following description taken in conjunction with the accompanying drawing which illustrates diagrammatically the keyboard transmitter according to the present invention, and shows in section a keyboard transmitter in which a transmitting drum 24, during its revolution, controls a contact 23 for transmitting facsimile signal impulses.

The transmitting drum 24 consists, for example, of insulating material in which the conducting segments 25 are imbedded. Instead of using a transmitting drum in which the segments are formed of metal imbedded in insulating material, cams may also be used which control the transmitting contacts, or metal discs, having their peripheries formed as shown in U. S. Patent 2,000,083, may be employed. Upon passing over these segments, when the contact 23 is in contact with the transmitting drum 24, a circuit is alternately closed and interrupted so that the corresponding facsimile signals are sent out. In the axial direction of the transmitting drum, are mounted next to each other, the various coded discs corresponding to the character signals. The transmitting drum 24 consists, for example, of forty different rings or discs, of which one is shown in section in the illustrated embodiment.

The actuation of key lever 1 is not dependent upon the position of the transmitting drum 24, but it may be depressed at any time with respect to the transmitting shaft 19. The trip member 2 is pivotally connected to the key lever 1, and biased counterclockwise by spring 27, draws down the holding pawl 3, thereby releasing the corresponding bell crank lever 4. The bell crank lever 4, under the influence of spring 5, is actuated counterclockwise, and through the lateral projection 38 thereon presses the trip member 2 to the right, against the action of spring 31, thereby disengaging said member from pawl 3, so that key lever 1 can no longer affect holding pawl 3. The counterclockwise rotation of bell crank lever 4 will be permitted because the blocking bar 6 is actuated leftwardly in timed relation thereto, as will presently appear.

Upon the depression of key lever 1, the universal bail 7 common to all the key levers, is actuated against the influence of its spring 28, so that the pull bar 8 rotates the clutch release lever 9 against the action of its spring 29, thereby releasing shaft 10, which has a high speed of rotation, for a single revolution. The auxiliary

shaft 10 is driven through a friction clutch (not shown). At the beginning of the rotation of shaft 10, cam 11, secured thereto, is rotated, and through cam follower roller 39, lever 12 is actuated counterclockwise, thereby carrying the key lever blocking bar 6 leftwardly. Blocking bar 6 is common to all blocking members 13, one of the latter levers being associated with each of the key levers 1. The key lever blocking bar 6 in being actuated counterclockwise is inserted in the cutout portion of all the blocking members 13 with the exception of the blocking member 13 corresponding to the depressed or operated key lever 1. The blocking bar 6 is rigidly connected to the cam follower lever 12 and, with the latter, is mounted on the pivot shaft 26. As a result of the displacement of the blocking lever 6 in this manner, all key levers except the one depressed are blocked against downward movement. The blocking members 13 associated with the key levers 1 are each normally held against the common stop member 14 by individual springs 30, thus when the blocking member 6 is deflected leftwardly upon the operation of a key lever, the member 13 associated with the operated key lever will be deflected leftwardly. Bell crank member 4, after the lock member 6 has been actuated leftwardly, will be rotated counterclockwise by its spring 5 to bring its shouldered end 15 into engagement with the blocking member 6, thus holding said member 6 in its leftward position against the action of its spring 32. The locking of the keyboard in this manner is maintained until the character symbol has been transmitted, as will presently appear. Should the operated key lever be released before the signal cycle initiated thereby has been completed, the spring 28 will act to lift said key lever to its horizontal or unoperated position, thus bringing notch 46 of bar 13 into engagement with bar 6 to prevent further depression during the present cycle.

To assure a single revolution of the shaft 10 in response to a single operation of a key lever 1, the lever 12 acts upon a projecting portion 40 of lever 3, to actuate said lever 3 counterclockwise against the action of its spring 36. The upper end of lever 3 is thereby disengaged from lever 9 to permit lever 9 to be rotated clockwise by a spring 29 to bring said lever 9 into operative engagement with stop disc 42, thus limiting the rotation of the shaft 10 to one revolution.

While the function described hereinbefore necessarily depends upon the depression of a key, the transference of the signaling condition, set up by the bell crank lever 4, to the transmitting device is timed by a cam carried upon the continuously revolving transmitting shaft 19. That is to say since the shafts 10 and 19 revolve independently, and in view of the fact that a key lever may be operated at any time or instant irrespective of the angular position of the shaft 19 (and hence the transmitting cylinder 24), nevertheless the transfer of the condition from the key lever portion of the transmitter to the transmitting drum portion is governed by a cam 20 fixed to the shaft 19. The cam 20 revolving with the transmitting shaft 19 in the direction of the arrow controls, through a roller 21, carried on lever 43, the control bar 22 common to all the bell crank levers 4. Pivotally carried on each bell crank 14 is a small bell crank lever 16 which acts, as will presently appear, to operate a contact control lever 17 to permit the engagement of contact 23 with

transmitting cylinder 24. When the bell crank lever 4 is tripped by the operation of lever 3 and is rotated counterclockwise by its spring 5, the bell crank lever 16 is carried rightwardly into closer proximity with the horizontal control bar 22. Thus, when control bar 22 is directed to the left (as will presently appear), bell crank lever 16 is rotated counterclockwise and then, together with the larger bell crank lever 4, is carried along to the left. The end of the horizontal arm of bell crank lever 16 encounters the enlarged end portion 18 of the contact control lever 17, and the lever 17 is depressed or actuated counterclockwise against the action of its spring 35. As a result, the transmitting contact 23 is released by shoulder 34 and, under the influence of spring 35, is rocked about a fulcrum and pin 37 and brought into engagement with the transmitting cylinder 24. As the cylinder 24 rotates, a facsimile signal is transmitted which corresponds to the arrangement of the segments 25 upon the periphery of the portion of the cylinder corresponding to the operated contact 23.

The timing of the transmission of the signal is controlled by cam 20. As the cam 20 rotates clockwise, follower roller 21 is first encountered by the apex 44 of the cam, and lever 43 is accordingly actuated clockwise against the action of its spring 33 so as to cause the bar 22, which is common to the contacts 23, to rotate all of the contacts 23 counterclockwise against the action of their individual springs 35 to bring the lower ends of said contact members into locking engagement with their respective shoulders 34 on the contact control levers 17. Immediately thereafter, the follower roller 21 rides into the depression 45 of cam 20 to cause lever 43 to rotate counterclockwise under the action of spring 33 so that bar 22 is actuated leftwardly to rotate all of the bell crank levers 4 clockwise against the action of their springs 5 to assure that the lower extremities of the vertical arms of all the bell crank levers 4 are brought into locking engagement with their respective holding pawls 3. If a bell crank lever 4 has been previously operated by a key lever 1 so that the shoulder 15 is engaged with the lock bar 6, and the small bell crank lever 16 is moved rightwardly, then just prior to the restoration of all the bell crank levers 4 to their latched or clockwise position, the small bell crank lever 16 of the actuated or operated bell crank lever 4 will be rotated counterclockwise to impinge its horizontal arm against the end portion 18 to effect the release of shoulder 34 from latching engagement with its associated contact lever 23. The disengagement of contact lever 23 from shoulder 34 occurs at a predetermined instant controlled by cam 20, which instant coincides with the registration of that portion of the transmitting cylinder ring or periphery indicative of the beginning of the facsimile signal corresponding to the key lever operated.

The restoration of the bell cranks 4, inclusive of the operated one, to the latched position (shown in the drawing) by bar 22 will also effect the disengagement of shoulders 15 from bar 6 to permit bar 6 to be returned to its rightward position under the influence of spring 32, thereby allowing bars 13 to be brought by their springs 30 against stop 14, and also bringing bar 8 again into operative engagement with the clutch release lever 9.

While the invention has been described and disclosed with regard to a particular type of ap-

paratus, it is manifest that various departures may be made from the disclosure without departing from the spirit and scope of the invention.

What is claimed is:

1. In a keyboard transmitter for facsimile printing telegraphs, a plurality of transmitting elements, one for each symbol, each having control surfaces corresponding to the light and dark areas of a scanned symbol, a contact for each transmitting element, a control member for each contact, a plurality of key levers, one for each contact, means associated with each key lever for controlling said control members, and means for removing said means from association with said key levers prior to the beginning of transmission of a facsimile system.

2. In a facsimile telegraph system, a transmitter having a plurality of transmitting elements each having lineally arranged control surfaces corresponding to the light and dark areas of a scanned character, a corresponding plurality of key operated mechanisms, means associated with each of said mechanisms for controlling said transmitting elements, and means for removing said means from the influence of said mechanisms prior to the beginning of transmission of a facsimile signal.

3. In a keyboard controlled facsimile telegraph transmitter, a plurality of transmitting mechanisms, one for each symbol, a corresponding plurality of key operated mechanisms, means for transmitting signal impulses controlled by said mechanisms, and means for timing the operation of said transmitting mechanisms independently of the instant of actuation of said key operated mechanisms.

4. In a keyboard controlled facsimile telegraph transmitter, a plurality of transmitting elements, one for each symbol, a contact for each element, a control member for each contact, a corresponding plurality of key operated mechanisms, and cam operated means associated with said elements for timing the operation of said control members independently of the instant of actuation of said key operated mechanisms.

5. In a keyboard controlled facsimile telegraph transmitter, a plurality of keys, a corresponding plurality of transmitting elements, one for each symbol, said elements being axially arranged and having control surfaces corresponding to light and dark areas of a scanned signal, a contact for each element, a control member for each contact, a key operated mechanism associated with each control member, and means common to said mechanisms and said control members and re-

moved from the influence of said keys for timing the operation of said control members independently of the time of actuation of said key operated mechanisms.

5 6. In a keyboard controlled facsimile telegraph transmitter, a plurality of keys, a corresponding plurality of transmitting elements, one for each symbol, said elements being axially arranged and having control surfaces corresponding to light and dark areas of a scanned signal, a contact for each element, a control member for each contact, a key operated mechanism associated with each control member, means common to said mechanisms and said control members and removed 10 from the influence of said keys for timing the operation of said control members independently of the actuation of said key operated mechanisms, and key locking means to preclude the premature operation of a succeeding key.

7. In a keyboard controlled facsimile telegraph transmitter, a plurality of transmitting mechanisms, one for each symbol, a corresponding plurality of key operated mechanisms, and means to control the operative relationship between said transmitting mechanisms and said key operated mechanisms whereby the transmitting mechanisms are removed from the influence of said key operated mechanisms prior to the beginning of transmission of a facsimile signal.

8. In a keyboard controlled facsimile telegraph transmitter, a plurality of transmitting mechanisms comprising constantly rotating code elements, a corresponding plurality of key operated start-stop mechanisms, and means to coordinate the cyclic operations of said elements and said key operated start-stop mechanisms.

9. In a keyboard controlled facsimile telegraph transmitter, a plurality of transmitting elements, one for each symbol, a contact for each element, a control member for each contact, a corresponding plurality of key operated mechanisms, and cam operated means associated with said elements for coordinating the operations of said contact control members and said mechanisms irrespective of the instant of actuation of the latter.

45 10. In a keyboard controlled facsimile telegraph transmitter, a plurality of transmitting mechanisms comprising constantly rotating code elements, a corresponding plurality of key operated mechanisms operable in irregularly recurring cycles, and means normally operable in regularly recurring cycles to coordinate the operations of said constantly operable elements and said irregularly operable mechanisms.
